UNITED STATES PATENT OFFICE.

WALTER CHRISTIE, OF WEEHAWKEN, NEW JERSEY.

LADDER-TRUCK.

1,311,552.

Specification of Letters Patent. Patented July 29, 1919.

Application filed November 21, 1917. Serial No. 203,207.

To all whom it may concern:

Be it known that I, WALTER CHRISTIE, a citizen of the United States of America, and a resident of Weehawken, county of Hudson, and State of New Jersey, have invented certain new and useful Improvements in Ladder-Trucks, of which the following is a specification, reference being had to the accompanying drawings, forming a part 10 thereof.

My invention relates to new and useful improvements in ladder trucks, and its object is to provide a motor-propelled truck for extension fire ladders, of improved construction.

Another object is to provide a simple and efficient arrangement by means of which the ladder actuating mechanism may be actuated by hand or may be driven by the motor 20 which is provided for propelling the vehicle.

A still further object is to improve upon the steering mechanisms for the truck and to provide a simple device for manually steering the rear wheels which may be readily 25 moved out of the path of movement of the ladder when desired.

In order that my invention may be thoroughly understood I will now proceed to describe the same in the following specification, and then point out the novel features 30 thereof in appended claims.

Referring to the drawings:

Figure 1 is a side elevation of a ladder truck made according to and embodying my 35 invention.

Fig. 2 is a plan view on a larger scale of the rear portion of my improved ladder truck, showing the rear steering gear. The position into which this steering gear may 40 be moved out of the way of the ladder is shown in broken lines in this figure.

Fig. 3 is a plan view partly in section, of the forward part of the apparatus showing somewhat in detail the ladder raising mechanism.

Fig. 4 is a sectional end elevation of a part of the mechanism which is shown in Fig. 3, the section being taken on the line 4-4 of the latter figure.

Fig. 5 is an end elevation, partly in section, of the rear steering gear, the section being taken on the line 5-5 of Fig. 2.

Fig. 6 is a side elevation on a still larger

scale, of a portion of the forward part of the apparatus. 55

Like characters of reference designate corresponding parts in all the figures.

10 designates the side frames of the apparatus, 11 its front wheels, and 12 its rear wheels. The front wheels are pivoted to the 60 front axle, at 13 and steered by a front steering wheel 14 in front of the driver's seat 15 by a mechanism 16 which is not a part of this invention.

17 is an internal combustion engine set 65 transversely of the side frames and arranged to be connected with or disconnected from the front wheels 11 by well known mechanisms which are not shown or described as they form no part of the present invention. 70

The rear wheels 12 are pivoted at 18 to the rear axle 19. From each of them extends an arm 20 and these are connected by a cross rod 21. Directly back of the rear wheels are raised side posts 22 and 23 cross-connected 75 by a brace 24. These form rigid parts of the frame of the vehicle. The side post 22 supports a vertical shaft 25, the upper end of which forms a pivotal support for a seat frame 26. 27 is the rear seat which is fastened to this seat frame. The other end of this frame is arranged to rest upon the side post 23 and to be connected therewith by a pin 28.

30 is a rear steering wheel on a vertical 85 shaft 31 rotatably supported in a forward extension of the seat frame 26. A sprocket wheel 32 on this shaft is connected by a sprocket chain 33 with a sprocket wheel 34 on shaft 25. On the lower end of shaft 25 90 is a worm and gear device 35 by means of which a rotation of shaft 25 in one direction or the other will move a lever 36 to the left or right. A rod 37 connects lever 36 with the cross rod 21. These parts are so arranged that when the steering wheel 30 is turned in either direction, the rear wheels 12 95 will be turned in the similar direction, but by a reduced amount.

Before describing the other parts of the 100 apparatus, I will show how this rear steering device is operated to get it out of the way of the ladder. When it is used to steer the vehicle by steering the rear wheels as just described, it has been assumed that the pin 105 28 is in place. When the apparatus is at

rest and it is desired to raise the ladder, the rear steersman without getting off of the seat 27, removes the pin 28. He now turns the wheel 30 in a right-hand direction and as it is easier for the seat frame to turn on its pivotal support than it is for the steering gear and the rear wheels to move, the pinion 34 will be held against rotation and consequently the seat frame will be swung out of the way of the ladder into the position in which it is indicated by dotted lines at 26A in Fig. 2. Of course the seat frame 26 and the parts which it supports may be brought back again by a reversal of this operation.

Near the forward part of the vehicle is a circular track 40 upon which is supported by anti-friction bearings, a turn-table 41. Pedestals 42 on this turn-table support a transverse shaft 43. 44 are frames to which is affixed the main ladder section 45. The other ladder sections are designated by 45A and 45B. These frames are pivoted on shaft 43 and comprise two internally toothed segments 46. Pinions 47 on a shaft 48 engage these segments. 49 is a bevel gear on shaft 48 arranged to be driven by a bevel pinion 50 on the upper end of a vertical shaft 51. The axis of this vertical shaft lies in the axis of turn-table 41. A worm gear 52 is on the lower end of shaft 51. 53 is a worm gear on a horizontal shaft 54 in mesh with worm gear 52. This shaft may be rotated by a hand-crank applied to a spindle 55 through gears 56 or may be connected by means of a clutch 57 to be driven by the engine through gears 58.

It is obvious that the ladder is raised or lowered by the rotation of shaft 54 in one direction or the other either through the power transmission mechanism which has just been described or the hand power mechanism.

60 is a hand lever near the driver's seat 45 for controlling the clutch 57. It is connected to slide a plunger 61 against a spring 62 which pushes the clutch out of its engaging position. 63 is an arm depending from the plunger and in engagement with the clutch.

60 On one of the segments 46 is a lug 65 which engages when the ladder has nearly reached a vertical position, the upturned end 66 of a slide rod, the other end of which engages a pivoted lever 67 on which is a roller 68 spring-pressed into engagement with the arm 63. When the lug acts upon these parts, the arm 63 will be forced to the left, as viewed in Fig. 6 to disengage clutch 57 whereby the motor is automatically disconnected from the ladder raising mechanism.

The ladder sections are extended by the usual mechanism actuated by a hand crank 69.

I will now describe briefly the mechanism 65 by means of which the turn-table 41 is ro-

tated. A circle of gear teeth 70 surrounds the track 40. 71 is a pinion in mesh with these teeth, and affixed to a short vertical shaft 72 supported in bearings on the turn-table. This shaft through gears 73 is connected with a longer vertical shaft 74, the upper end of which is connected by gears within a gear casing 75 with a hand wheel 76. By turning the hand wheel the turn-table and the ladder which is mounted on it may be rotated. As the axes of the turn-table 41 and of the vertical transmission shaft 51 are coincident, this rotation of the turn-table does not affect the motor ladder raising mechanism.

80

I intend no limitations other than those imposed by the appended claims.

What I claim is:

1. A ladder truck comprising front and rear wheels, a ladder, a pivotal support therefor near the front end of the truck, raising and lowering mechanism for swinging the ladder about its pivotal support, a steering gear for the rear wheels comprising a frame adapted to extend transversely across the ladder, a pivotal support for said frame at one side of the ladder, and means for swinging said frame about its pivotal support.

2. A ladder truck comprising front and rear wheels, a ladder, a pivotal support therefor near the front end of the truck, raising and lowering mechanism for swinging the ladder about its pivotal support, a steering gear for the rear wheels comprising a frame adapted to extend transversely across the ladder, a vertical shaft at one side of the ladder arranged to form a transmission element of the steering gear and to serve as a pivotal support for said frame, and means for swinging said frame about its pivotal support.

3. A ladder truck comprising front and rear wheels, a ladder, a pivotal support therefor near the front end of the truck, raising and lowering mechanism for swinging the ladder about its pivotal support, a steering gear for the rear wheels comprising a frame adapted to extend transversely across the ladder, a vertical shaft at one side of the ladder arranged to form a transmission element of the steering gear and to serve as a pivotal support for said frame, a steering wheel supported on said frame, connections between said steering wheel and said shaft, and releasable means for holding said frame in its transverse position, said steering wheel and connections being operative to swing the frame about its pivotal support when the holding means is released.

4. A ladder truck comprising front and rear wheels, a ladder, a pivotal support therefor near the front end of the truck, raising and lowering mechanism for swinging the ladder about its pivotal support, a steering

125

110

115

120

130

gear for the rear wheels comprising a frame adapted to extend transversely across the ladder, a vertical shaft at one side of the ladder arranged to form a transmission element of the steering gear and to serve as a pivotal support for said frame, a seat supported on said frame, a steering wheel on the frame in front of the seat, connections between said steering wheel and said shaft,

and means for holding said frame in its transverse position, releasable from said seat, said steering wheel and connections being operative to swing the frame about its pivotal support when the holding means is released.

In witness whereof I have hereunto set my hand this 19th day of November, 1917.

WALTER CHRISTIE.
